METHOD AND APPARATUS FOR MINING AND TUNNELING

Joseph Francis Joy, Franklin, Pa., assignor to
Sullivan Machinery Company, a corporation of
Massachusetts

Application December 22, 1934, Serial No. 758,744

35 Claims. (Cl. 262—28)

This invention relates to methods of and apparatus for cutting kerfs, and more particularly, in certain embodiments thereof, to methods of and to apparatus especially useful for tunneling. An object of this invention is to provide an improved method of and apparatus for cutting kerfs. Another object of this invention is to provide an improved method of and apparatus for mining and especially for tunneling. Another object is to provide an improved method of and apparatus for tunneling whereby a tunnel may be formed by initially cutting a central pilot bore and thereafter cutting a concentric main tunnel bore. A further object is to provide an improved tunneling apparatus known as a tunnel saw for forming, with a circular sawing action, a tunnel bore in accordance with the improved tunneling method. A still further object is to provide an improved tunnel saw having improved adjusting and supporting structure for the saw blade whereby circular pilot and main tunnel bores of different diameters may be cut in the tunnel face. Yet another object is to provide an improved cutting apparatus for cutting a pilot bore in which operates the cutting apparatus for cutting the main tunnel bore, the cutting device for cutting both bores being embodied in a single tunneling machine for interchangeability simply by the substitution of the pilot bore cutting devices for the main bore cutting devices and vice versa. A further object is to provide an improved tunnel saw for cutting out, with a circular sawing action, the tunnel bore by means of a saw blade movable in an arcuate path about an axis coincident with the tunnel bore axis. Yet another object is to provide an improved adjustable supporting structure for the saw blade whereby the latter may be positioned at variable distances from the axis of blade swing, thereby enabling tunnel bores of variable size to be formed. Another object is to provide an improved method of and apparatus for tunneling whereby the tunnel bore is formed by cutting out a circular slot about the tunnel bore periphery, thereby to form a circular core in the tunnel face. Yet another object is to provide an improved method of and apparatus for tunneling whereby a rectangular pilot bore may be initially cut in the tunnel face prior to the cutting out of the main circular tunnel bore. A still further object of this invention is to provide an improved hydraulically operated tunnel saw where- 50 in the various mechanisms of the apparatus are hydraulically operated and controlled in an improved manner. A still further object is to provide an improved tunnel saw having an improved

adjustable supporting structure for the saw blade, and improved means for driving the saw blade, for adjusting the supporting structure and for propelling and controlling the apparatus. Yet another object of my invention is to provide an improved kerf-cutting apparatus having improved supporting means for a kerf-cutting element. Still another object of my invention is to provide an improved supporting structure for a kerf-cutting element. These and other objects and advantages will, however, hereinafter more fully appear.

In the accompanying drawings there are shown for purposes of illustration two forms which the invention may assume in practice.

In these drawings—

Fig. 1 is a plan view of one illustrative embodiment of the invention incorporated in the form of an improved tunnel saw showing the adjusting structure for the pilot hole cutter.

Fig. 2 is a side elevational view of the tunnel saw shown in Fig. 1, different adjusted positions of the saw blade being indicated in dotted lines.

Fig. 3 is an enlarged view in longitudinal vertical section taken substantially on line 3—3 of Fig. 1.

Fig. 4 is a transverse sectional view taken substantially on line 4—4 of Fig. 3.

Fig. 23 is an enlarged vertical sectional view with parts shown in elevation taken substantially in the plane of line 23—23 of Fig. 20.

20. Fig. 24 is a cross sectional view taken substantially on line 24—24 of Fig. 23.

Fig. 25 is a detail view showing the rotating head lock.

Fig. 26 is a detail sectional view taken on line 25. 26—26 of Fig. 25.

Fig. 27 is a diagrammatic view showing the tunnel saw in cutting position during the formation of the pilot hole in accordance with one method.

30. Fig. 28 is a diagrammatic view showing the improved tunnel saw in position within the pilot hole during the formation of the main tunnel bore in accordance with the method of Fig. 27.

Fig. 29 is a diagrammatic view similar to Fig. 35. 28 showing the tunnel saw in position to effect one method of sumping the saw blade.

Fig. 30 is a diagrammatic cross sectional view of the pilot bore showing the tunnel saw in operating position therein.

40. Fig. 31 is a diagrammatic cross sectional view showing the operation of the tunnel saw during the formation of the main tunnel bore.

Fig. 32 is a diagrammatic view similar to Fig. 28 showing a different tunneling method for forming the tunnel bore.

Figs. 33 and 34 are diagrammatic views similar to Figs. 27 and 28 showing still another tunneling method.

The invention in its different aspects is capable 50 of embodiment in various forms, and I have herein shown it incorporated, in Figs. 1 to 16 inclusive, in one form of tunnel saw and, in Figs. 17 to 26, in a different form of tunnel saw; it being understood, however, that from its apparatus aspect it is not limited to tunnel sawing instrumentalities.

In the illustrative embodiment of the invention disclosed in Figs. 1 to 16, inclusive, there is shown generally in Figs. 1 and 2, a tunnel saw generally 60 designated 1 having a pilot bore forming cutter 2 supported by an adjustable supporting structure generally designated 3 mounted on a rotatable head 4. Shown in Fig. 14 is a main tunnel bore forming cutter 5 supported by adjustable supporting structure generally designated 6 of an extensible character, on the rotatable head 4, the cutters 2 and 5 and their respective supporting structures 3 and 6 being interchangeable to effect the different bore forming operations in a 65 manner to be later described. The rotatable head 4, on which the structures 3 and 6 may be interchangeably mounted, is journaled for rotation about a horizontal axis extending longitudinally of the tunnel saw, and is provided with 70 an elongated tubular bearing sleeve 8 journaled

in bearings 9, 9 supported within a cylindrical bearing support 10 secured to the upper frame of a truck body 11. The truck body of the tunnel saw is of elongated and extremely heavy form to provide stability, and is mounted on truck wheels 12, 12 adapted to run along a trackway 13.

Now referring more particularly to the pilot bore forming cutter 2 and its supporting structure 3 known as the short boom, it will be noted that the rotatable head 4 overhangs the forward end of the truck body and has integral forwardly projecting parallel frame portions 14, 14 in which are supported the ends of a transverse pivot shaft 15 arranged with its axis lying in a vertical plane 1 perpendicular to the head axis. Pivotally mounted on this pivot shaft is an elongated arm or boom 16 which has secured at its outer extremity a bifurcated or yoke-shaped frame 17. Swingably mounted between the furcated arms 2 of this yoke-shaped frame is a support 18 on which the cutter 2 is pivotally mounted for swinging movement about a transverse axis perpendicular to the axis of the swinging support 18 and parallel with the boom pivot axis. The cutter 2 is in the form of an elongated plane cutter bar or saw blade 19 having mounted thereon, for circulation about its margin, an endless cutter or saw chain 20. Mounted on the boom 16, at the rearward portion thereof in advance of the pivot shaft 15, is a motor 21, herein preferably of the reversible electric type, having its casing 22 supported by and secured to the boom frame. The power shaft 23 of this motor is arranged with its axis extending longitudinally of the boom at right angles to the pivot shaft axis. The driving connections between the motor power shaft 23 and the saw chain comprise a shaft 24 connected by a flexible coupling 25 to the motor power shaft and suitably journaled within the boom frame. This shaft 24 is splined at 26 throughout a major portion of its length and is connected by a coupling 27 to an alined shaft 28, the coupling 27 being herein of tubular form within which the splined shaft 26 is adapted to telescope in a manner to be later described. As shown in Fig. 3, keyed to the forward end of the shaft 28 is a bevel gear 29 meshing, as shown in Fig. 4, with a bevel gear 30 in turn meshing with a bevel gear 31 keyed to a shaft 32 arranged with its axis coincident with the pivotal axis of the swingable support 18. The arm 33 of the yoke-shaped frame 17 is made hollow and houses therein the bevel gears 30 and 31, and is provided with bearing supports on which these bevel gears are journaled. Herein formed integral with the shaft 32 is a bevel gear 34 meshing with a bevel gear 35 arranged in a chamber 36 formed within the swingable support 18. This gear is connected by a friction slip clutch 37 of the multiple disc type to a shaft 38, the clutch 37 being set at a predetermined pressure to slip upon overloading of the saw chain, thereby to prevent injury to the driving parts. The shaft 38 is suitably journaled within the swingable support 18 and is arranged with its axis coincident with the axis of swinging movement of the saw blade, and has fixed thereto a chain sprocket 39 engaging and driving the saw chain 20. As above referred to, the saw blade 19 is mounted on the swingable support 18 for swinging movement with respect thereto, and the pivotal mounting for the saw blade comprises a blade hanger 40 having a circular bearing support 41 mounted on bearing sleeves 42 surrounding and supported

by a cylindrical support 43 integral with the swingable support 18. The means for locking the saw blade in its different angularly adjusted positions with respect to the support 18 comprises a locking pin 44 rotatably mounted and retained in a bearing sleeve 45 supported within a boss 46 integral with the support 18. This pin has a projecting locking portion 47 adapted to be turned into locking relation with any one of a plurality of notches 48 formed in an arcuate flange 49 integral with the saw blade hanger 40. These locking recesses 48 are so positioned about the flange periphery that the saw blade may be locked in either a forwardly projecting or rearwardly projecting position with its major axis lying in a vertical plane including the longitudinal axis of the boom, or in right angle positions at either side of the boom.

The means for swinging the boom about its pivot with respect to the rotatable head 4 and for swinging the saw blade support 18 about its pivot with respect to the boom will now be described. As shown in Fig. 6, mounted on aligned pivot pins 50, 50 supported within the parallel frame portions 14, 14 of the rotatable head 4, at opposite sides of the boom, is a pair of hydraulic rams 51, 51, the pivot pins 50 being arranged with their axes parallel with the axis of the hinge pin 15 so that the hydraulic rams may swing in the same planes as the boom. These hydraulic rams each comprise, as shown in Fig. 11, a cylinder 52 containing a reciprocable piston 53 having a piston rod 54 projecting forwardly through the packed front head 55 of the cylinder and pivotally connected by a hinge pin 56, supported within projecting lugs 57 integral with the boom frame, to the outer extremity of the boom frame. The means for swinging the saw blade support 18 with respect to the boom frame 17 comprises a hydraulic ram 60 having a cylinder 61 suitably fixed to the boom frame and containing a reciprocable piston 62. This piston has a rearwardly extending piston rod 63 projecting through the packed rear head 64 of the cylinder 61 and secured at 65 to a cross member 66. Pivotally connected at 67 to the ends of this cross member is a pair of parallel links 68 extending along the sides of the cylinder 61 and pivotally connected at 69 at their outer ends, to a projecting lug 69a integral with the swingable support 18. It will thus be seen that when hydraulic pressure is supplied to the hydraulic rams 51, 51, the boom structure 3 may be swung relative to the rotatable head 4 through a relatively wide range of adjustment from a longitudinal position to a position at right angles with respect to the head axis, and when hydraulic pressure is supplied to the ram 60, the saw blade support 18 may be swung through a relatively wide range with respect to the boom to move the saw blade through a relatively wide angle about the support pivot from a position extending lengthwise of the boom to a right angle position. By locking the hydraulic pressure within these rams, the parts may be maintained in their adjusted positions.

The mechanism for rotating the head 4 relative to the truck body to move the cutter support and adjusting structure into different positions about the head axis comprises a pair of hydraulic cylinders 70, 70 each containing a reciprocable piston 71. These cylinders are mounted within the truck body and arranged in parallel relation on axes extending longitudinally of the truck body and spaced equi-distantly from the longitudinal vertical center of the truck body. These cylinders

are provided with a front head plate 72, to which they are welded, and the pistons 71 have rearwardly extending piston rods 73, 73 projecting through the packed rear heads 74 of the cylinders. Secured to the rear ends of the piston rods 73 are brackets 75 each having journaled thereon a cable guiding pulley 76, while journaled on brackets 77 secured to the front head plate 72 are cable guiding pulleys 78. A pair of cables 79, 79 are connected to pin-like projections or abutments 80, 80 (Fig. 7) secured to the rotatable head 4. The ends of these cables extend outwardly from their connections with the head through openings 81 in the head frame and extend in opposite directions around an annular guiding groove 82 formed on the head periphery, the cables passing from this guiding groove around the front guide pulleys 78 and extending rearwardly along the sides of the cylinders 70, 70 to the guide pulleys 76, 76. The cables pass around these guide pulleys 76 and extend forwardly along the cylinders to a point of connection at 83 with the frame of the truck body. The cables are connected to the truck body frame each by a wedge block 84 (Fig. 9) mounted within a socket 85 in a block 86 secured to the front plate 72, the cable extending through openings 87 formed in this plate. It will thus be seen that when hydraulic pressure is supplied to one or the other of the cylinders 70, 70, the head 4 may be rotated in one direction or the other, through the cable and pulley connections, above described. The hydraulic pressure locked within these cylinders maintains the head in its adjusted position.

The propelling means for the apparatus for driving the truck wheels through a wide range of speeds comprises, as shown in Figs. 6 and 13, a pair of hydraulic, variable speed motors 90, 90 herein of the intermeshing gear type, each comprising a gear housing 91 containing intermeshing rotor gears 92. One of the rotor gears of each motor is fixed to a shaft 93 connected by a coupling 94 to a shaft 95 suitably journaled within a gear housing 96 suitably secured to the truck body. Fixed on each of the shafts 95 is a worm 97 meshing with a worm wheel 98, these worm wheels being fixed respectively to the front and rear truck wheel axles 99. It will thus be seen that when hydraulic pressure is supplied to the motors 90, the truck wheels may be driven to propel the apparatus along the trackway 13 and by varying the supply of hydraulic pressure to these motors, the speed of truck wheel drive may be varied through a relatively wide range. The motors 90 are reversible so that the truck wheels may be driven to propel the apparatus in the reverse direction. Formed on the hubs of the truck wheels, at opposite sides of the truck, is a drum flange 100 about which a cable may be coiled or snubbed, and the free end of this cable may be connected to a suitable anchor so that the cable and drum may, at times, supplement the truck wheel drive. Carried within the truck body is a motor 101, similar to the motor 21 on the boom structure, having its power shaft 102 connected to an oil pump 103, herein preferably of the intermeshing gear type, arranged in a tank 104 which forms an oil reservoir. The pump 103 is adapted to pump oil under high pressure from the reservoir to the various hydraulic devices of the apparatus, as hereinafter described. Mounted on the rearward end of the truck body is a cable reel 106 on which is wound an electrical conductor cable 107 through which electrical energy

may be conducted, under the control of suitable electrical controlling apparatus, to the electric motors 21 and 101. This cable reel is driven by a hydraulic motor 108, herein likewise of the intermeshing gear type, having one of its rotor shafts driving a pulley 109 connected by a belt 110 to a pulley 111 secured to the reel shaft.

Hydraulic jack devices are provided for jacking the tunnel saw in position on the trackway during the main tunnel bore sawing operation and comprise, as shown in Fig. 12, a pair of vertical hydraulic jacks 112, 112 mounted in parallel relation on a horizontal plate 113 of the truck body at the opposite sides of the latter and each containing a piston 114. Each piston is provided with an upwardly extending piston rod 115 projecting through the packed upper head 116 of the jack cylinder and each piston rod is provided with a socket 117 for receiving a jack pipe 118. It will thus be seen that when hydraulic pressure is supplied to the jack cylinders below the pistons 114, the jack pipes may be moved upwardly into engagement with the roof of the pilot bore to jack the apparatus in position on the track rails. During this jacking operation, the truck wheels may be locked against rotation by trapping the fluid within the motors 90 or by the intermeshing worm gearing 97, 98 which may be self-locking.

As mentioned above, the improved tunnel saw is provided with interchangeable supporting structures for the cutters, and the relatively short adjustable supporting structure 3 may be supplanted by the relatively long adjustable supporting structure 6 shown in Figs. 14, 15 and 16. As above mentioned, the supporting structure 3 is employed during the pilot bore forming operation, while the much longer extensible supporting structure 6 is employed during the forming of the main tunnel bore. When the extensible supporting structure 6 is employed, the boom frame 17 is detached from the outer extremity of the boom, and secured in its place is a bearing frame 120 supporting a bearing sleeve 121. Telescopically arranged within the boom 16 is a tubular frame portion 122 of an extension head 123. Secured to the outer extremity of this extension head 123 is the frame 17 on which the saw blade support 18 is swingably mounted, the frame 17 being formed for connection with either the outer extremity of the boom frame 16 or the extension frame 123. The short tubular coupling 27 is detached from its connection with the shafts 24, 28 and has substituted therefor an elongated tubular coupling member 124 for connecting the shaft 24 with the shaft 28 when the extension frame is employed. The tubular frame 122 telescopes within the boom frame 16 and is adjustable axially with respect thereto to vary the effective length of the boom, and the splined telescopic connection between the shaft 28 and the coupling 124 enables the driving relation between the shafts 26 and 28 to be maintained irrespective of the adjusted position of the extension frame 122. The means for adjusting the extension frame longitudinally with respect to the boom frame 16 comprises a pair of hydraulic rams 126, 126 mounted on the opposite sides of the boom frame 16 and each comprising a cylinder 127 containing a piston 128. The pistons have forwardly extending piston rods 129 projecting through the front packed heads 130 of the cylinders, and the forward extremities of these rods are pivotally connected at 131 within projecting lugs 132 integral with the frame extension 123. The tubular frame 122 is splined at 133 within the boom

frame 16 to prevent rotation of the frame 122 with respect to the boom frame. When hydraulic pressure is supplied to the hydraulic rams, the extension frame may be moved axially inwardly or outwardly with respect to the boom frame 16, thereby to vary the effective length of the boom structure on which the cutter saw blade support 18 is swingably mounted.

The hydraulic system for the various hydraulically operated mechanisms of the tunnel saw will now be described. As above pointed out, the motor driven pump 103 is adapted to supply hydraulic pressure from the reservoir 104 to the various hydraulic mechanisms, and arranged at the operator's station near the front end of the machine is a valve box 135 containing control valves for controlling the hydraulic rams 31 and 60, the head rotating cylinders 70 and the anchor jack cylinders 112 and extension cylinders 126. Located near the valve box 135 is a valve box 136 containing valves for controlling the flow of hydraulic pressure to the oil motors 90 and 108, while arranged in a valve box 137 are by-pass valves for regulating the hydraulic pressure. As shown diagrammatically in Fig. 17, leading from the discharge side of the oil pump 103 to the valve box 131 are supply conduits 138 and 139, while leading from the valve box 137 is a conduit 140 through which hydraulic pressure is supplied to the various hydraulic mechanisms. A return conduit 141 connects the valve box 137 with the oil tank. As shown in Fig. 18, the conduit 138 is connected to the supply conduit 140 by a passage 142 in the valve casing, while the conduit 139 communicates with a passage 143 communicable through a passage 144 with the passage 142 and through a passage 145 with a chamber 146 with which the return conduit 141 communicates. The passages 144 and 145 are controlled by end seating valves 147 and 148 respectively, having a suitable operating lever 149. When the lever 149 is swung into the position shown, both the pressure supply conduits 138 and 139 communicate with the supply conduit 140 while the passage 145 is closed. When the lever 149 is swung into its opposite position, the passage 144 is closed by the valve 147 while the passage 145 is open so that the conduit 138 communicates with the supply conduit 140 and the conduit 139 is connected through the passage 145 and chamber 146 with the return conduit 141. The supply conduit 140 is connected by a conduit 158 controlled by a valve 151 and communicating through a passage 152 (see Fig. 3) formed in the saw blade hanger 40, and this passage in turn is connected through a longitudinal duct 153 in the saw blade 19 through which high pressure oil is conducted to the guides for the saw chain to lubricate the latter and also to the slot cut by the saw chain to lubricate the cuttings, thereby to facilitate the cutting function. The conduit 140 leads from the valve box 131 to the valve box 135 and is connected by a supply conduit 154 to the valve box 136. The casing of the valve box 135 is formed with a plurality of vertical bores, herein five in number, respectively having arranged therein control valves 155, 156, 157, 158 and 159 each provided with an actuating handle. These valves are provided with upper annular channels 160, 161, 162, 163 and 164, respectively, all communicating with an upper exhaust chamber 165 in the valve casing connected by a conduit 166 to a return conduit 167 leading back to the oil tank. The supply conduit 140 communicates with a pressure supply passage 168 connecting the lower

ends of the valve bores together. The bore for the valve 155, which is herein the jack control valve, is connected by a conduit 169 and branched conduits 170 and 171 to the lower ends of the anchor jack cylinders 112, the upper ends of these anchor jack cylinders being connected by branched conduits 172 and 173 to a conduit 174 likewise leading to the bore for the valve 155. The bore for the valve 156, which is herein the lift cylinder control valve, is connected by a conduit 175 to branched conduits 176 and 177 communicating with the forward ends of the lifting ram cylinders 51, while the rear ends of these lifting ram cylinders are connected through branched conduits 178 and 179 to a conduit 180 likewise communicating with the bore of the valve 156. The bore of the valve 157, which is herein the extension cylinder control valve, is connected through a conduit 181 through branched conduits 182, 183 to the forward ends of the extension cylinders 126, the rear ends of these cylinders being connected through branched conduits 184, 185 with a conduit 186 likewise communicating with the bore of the valve 157. The bore of the valve 158, which herein is the saw blade tilting cylinder control valve, is connected through a conduit 187 to the forward end of the tilt cylinder 60, the rear end of the tilt cylinder being connected by a conduit 188 likewise with the bore of the valve 158. The bore of the valve 159, which herein is the head rotating cylinder control valve, is connected by a conduit 189 with the forward end of one of the swing cylinders 70 and through a conduit 190 with the other swing cylinder 70. The rear ends of the swing cylinders are respectively connected through return conduits 191 and 192 to the oil tank. Each of the valves 155, 156, 157, 158 and 159 has formed on its periphery a pair of longitudinal grooves, one groove for connecting its return conduit with the exhaust chamber 185 and the other for connecting the supply conduit with the pressure supply passage 188. It will thus be seen that the control valves 155, 156, 157, 158 and 159 may be operated to supply pressure fluid to or exhaust fluid from the anchor jacks, the boom lift rams, the boom extension cylinders, the saw blade support tilt cylinder and the head rotating cylinders.

As above pointed out, the valve box 136 is connected through a conduit 154 to the pressure supply conduit 140. This valve box is connected by a return conduit 193 to the return conduit 167. The valve box 136 is provided with a lower chamber 194 and an upper chamber 195, and these chambers communicate with vertical valve bores containing control valves 196 and 197, the valve 196 constituting a reverse valve, and the valve 197 constituting the control valve for the oil motors 90 and 98. The valves 196 and 197 are formed at their upper ends with annular channels 198 and 199, respectively, communicating with the upper chamber 195. The supply conduit 154 is communicable with the lower chamber 194, while the return conduit 193 is communicable with the upper chamber 195. The bore for the valve 197 is connected through conduits 200 and 200^a with one of the oil motors 90 and through conduits 201 and 202 with the other of the oil motors 90. The conduits 200 and 200^a are connected through a conduit 203 to the intake chamber of the oil motor 98, the discharge chamber of this motor being connected by a return conduit 204 to the oil tank. The valve 197 has formed on its periphery three longitudinal slots 205, 206 and 207 communicating with the lower chamber 194, while longitudinal grooves 208, 209 and 210 on the valve periphery connect the upper chamber 195 with an annular chamber with which the return conduit 193 communicates. The body of the valve 197 is traversed by an angular passage 211. The reverse valve 196 has formed on its periphery a pair of longitudinal grooves 212 and 213 and when the valve 196 is in the position shown in Fig. 17, pressure fluid may flow from the supply conduit 154 through the groove 212 to the lower chamber 194, while the groove 213 connects the upper chamber 195 with the return conduit 193. Thus, at that time, the upper chamber 195 is an exhaust chamber, while the chamber 194 is a supply chamber. When the control valve 197 for the oil motors 90 and 98 is in the position shown in Fig. 17, pressure fluid may flow from the lower supply chamber 194 through the longitudinal grooves on the valve 197 and supply conduits 200 and 201 to the motors 90, these motors exhausting through conduits 200^a, 202 and the grooves 208 and 209 on the valve connected to the exhaust chamber. When the reverse valve 196 is moved into its opposite position, pressure fluid is supplied from the conduit 154 to the upper chamber 195, while the lower chamber 194 is connected to the return conduit 193. It will be evident that when the valve 197 is in the position shown in Fig. 17, the motors 90, 98 operate in parallel. When the motor control valve 197 is turned into a position wherein the angular passage 211 connects the conduit 201 with the conduit 200^a, pressure fluid may flow through groove 206 on the valve and through conduit 200 to the inlet of one of the motors 90, while the exhaust from this motor flows through conduit 200^a through the angular passage 211 in the valve and through conduit 201 to the inlet of the other motor 90, the discharge from this latter motor passing through the conduit 202 and groove 210 in the valve communicating with the exhaust chamber. It will thus be seen that at this time the motors 90, 98 operate in series, the discharge from one flowing to the intake of the other. By changing the position of the control valve the supply of pressure fluid to the motors 90 may be varied, and as a result the motor speed may be varied through a wide range. Further, by suitable manipulation of the reverse valve 196 the direction of rotation of the motors 90, 98 may be reversed at will. When the motors 90, 98 operate in a direction to propel the apparatus in a rearward direction along the trackway, pressure fluid flows through conduit 203 to the intake of the reel driving motor 108 so that as the apparatus moves rearwardly along the mine trackway, the reel 108 is driven to wind in the conductor cable 107. When the motors 90, 98 are operated in a direction to propel the apparatus in the forward direction along the trackway, the intake of the motor 108 is connected to the return conduit 204 so that the conductor cable may freely unwind from the cable reel. In any position of the valves above described, when it is desired to supply more pressure to the various hydraulic mechanism, the by-pass valves 147, 148 are positioned to supply pressure from both the supply conduits 138, 139 to the supply conduit 140.

Now referring to the modified form of construction shown in Figs. 20 to 26, inclusive, it will be noted that the rotatable head 4 has its tubular bearing sleeve 8 journaled in a cylindrical bearing support 220 herein secured to a horizontal

turntable 221. As shown in Fig. 23, the turntable frame has a depending column or post 222 journaled in bearing sleeves 223 carried by a cylindrical bearing support within the truck body 224. 5 This turntable 221 on which the head 4 is mounted is provided for swinging the cutter supporting structure, generally designated 225, in a horizontal direction with respect to the truck body. Pivotally mounted at 226 on the head is a boom 10 227 having swinging mechanism in the form of hydraulic rams 228 similar to those described above for swinging the boom structure 3. In this embodiment of the invention, there is rotatably mounted within the boom 227 for rotation about 15 the longitudinal axis of the boom, a boom extension or head 229 which carries the frame 17 on which the saw blade support 18 is swingably mounted. Carried by this rotatable boom extension 229 is the hydraulic ram 60 for swinging the 20 saw blade support 18 with respect to the boom extension. The means for rotating the boom extension 229 about the longitudinal axis of the boom 227 comprises a pair of hydraulic cylinders 230, 230, each containing a reciprocable piston 25 having a rearwardly projecting piston rod 231. Each of these piston rods carries a bracket 232 on which is journaled a guide pulley 233. Passing over both of these pulleys 233, 233 is a cable 234 anchored at each end to the boom 227, the 30 cable passing from the pulleys 233 around pulleys 235 journaled on the forward heads of the cylinders 230 and having its intermediate portion making several turns around and at its middle anchored to a drum 236 which is fixedly secured 35 to the rotatable boom extension or head 229. Suitable valve means, similar to those above described, is provided for controlling the supply of pressure to and the exhaust from the cylinders 230 to effect reciprocation of the pistons, thereby 40 to rotate the drum 236, together with the boom extension head 229, with respect to the boom 227. The means for rotating the head 4 and the turntable 221 about their respective axes comprises the horizontal swing cylinders 70, 70 mounted 45 within the truck body. Rotatably mounted in coaxial relation with the turntable is a cable drum or large sheave 240, while journaled on an axis parallel with the axis of the drum 240 at the rear of the latter is a guide pulley 241. Journaled 50 on the turntable frame near the head 4 is a pair of angularly disposed guide pulleys 242, 242. A pair of cables 243, 243 are fixed at one end to the truck body, and these cables pass around the guide pulleys 16, 16 and then extend rearwardly 55 around the opposite sides of the guide pulley 241, the cables crossing after they leave this guide pulley and passing around the opposite sides of the drum or sheave 240. The cables extend from the drum 240 around the guide pulleys 242, 242 60 and then wrap around the cable groove 82 on the head 4, the cables being secured at this end in the manner shown in Fig. 7. The means for locking the head 4 against rotation during turntable rotation comprises a locking pin 245 guided with- 65 in a bracket 246 mounted in the turntable frame and having an operating lever 247. This locking pin is adapted to project within locking recesses 248 formed in the head frame so that when one of these locking recesses registers with the pin, 70 the pin may be slid inwardly within the recess to lock the head against rotation. The turntable 221 is provided with a similar locking pin 249 guided on the truck body and having an operating lever 250 so that the turntable may be locked 75 against rotation during head rotation. From the

foregoing, it will be evident that when hydraulic pressure is supplied to the cylinders 70, 70, the turntable and head may be selectively rotated about their respective axes in either of opposite directions, depending upon which cylinder is operated. Otherwise this form of the invention is the same as that above described.

Various methods in which the improved tunnel saw may be operated will now be described. As shown in Fig. 27, the tunnel saw is in operating 10 position within the pilot bore A with the pilot bore cutter adjusting means 3 mounted on the rotatable head 4, and this short boom structure is revolved about the axis of the head 4 to rotate the cutter in a circular path to cut out a circular 15 slot, thereby to form the pilot bore, the cutter sawing out, with such circular sawing motion, a cylindrical core which is removed in any suitable manner, as by drilling and blasting, after the 20 circular sawing cut is completed. Fig. 30 clearly shows the tunnel saw in its pilot bore cutting position. During the cutting of the pilot bore in the manner shown in Figs. 27 and 30, the tunnel saw operates along the trackway in a forward 25 direction, and when the pilot bore has been cut to the desired depth, the machine is backed out of the pilot bore and then suitably turned end, for end on the trackway and the relatively long extensible boom structure 6 substituted for the 30 short boom structure 3. When the tunnel saw is in the position shown in Figs. 28 and 31, the boom is swung at right angles with respect to the head axis and the saw blade swung into a rearward position with its major axis extending 35 parallel with the saw body. The machine is then propelled rearwardly along the trackway to sump the saw blade, by an endwise feeding movement, into the material to be cut. After the sumping operation has been completed, the head 4 is rotated to move the saw blade in a circular 40 path to cut out the main tunnel bore B, as shown in Fig. 31. In certain instances, the cutter is operated in a circular path from one side of the tunnel to the other, leaving a flat bottom C, as shown in Fig. 31, and the core thus formed by 45 the cutter is removed in a suitable manner, as by drilling and blasting. If desired, however, the saw blade may be moved in a complete circular path to form an annular core in accordance with the method shown in Fig. 32. As shown, the core thus formed may be blocked up, as by suitable wedge blocks 260, and after the annular core has been formed it is suitably shot down, as by drilling and blasting. Instead of sumping the saw blade into the material to be cut by propelling the tunnel saw in a rearward direction bodily along the trackway, the saw blade may be sumped into the tunnel face in accordance with the method shown in Fig. 29, that is by swinging the boom relative to the head while the latter remains stationary and at the same time retracting the boom and swinging the saw blade support 18 with respect to the boom. It will thus be seen that purely by swinging and retractive movements of the boom and swinging movement 55 of the saw blade support the cutter may be sumped in. In accordance with the tunnel forming method shown in Figs. 33 and 34, the tunnel saw is not turned around on the trackway after the pilot bore has been completed, the saw, in accordance with this method, operating in a forward direction to form the pilot bore A, and after the completion of the pilot bore, operating in the reverse direction to form the main tunnel bore B. For operating in accordance with the 60

method shown in Fig. 31, the tunnel saw is provided with a modified form of mounting, as shown in Figs. 20 to 26, inclusive. The saw blade may be operated in a circular path to form the curved sides of the tunnel and after the completion of the circular sawing motion, the turntable 221 may be rotated with respect to the truck body to swing the saw blade horizontally in a plane path to cut the plane bottom C of the tunnel bore. Also by the use of the mechanism shown in the modified form of construction, the saw blade may be swung vertically in its plane to form the plane side of a rectangular pilot bore by rotating the extension boom 229 relative to the boom 227 to position the saw blade in a vertical plane. It will thus be evident that in this modified form of the construction the saw blade may be swung either horizontally and vertically in plane paths as well as in an arcuate path. It will be evident that during any of the sawing methods above described, the tunnel saw may be propelled along the trackway at any desired speed under the control of the hydraulic truck wheel driving motors, and the truck wheels may be locked against rotation by trapping the oil within these motors. During the circular sawing motion of the saw blade, the body of the tunnel saw is jacked in position against the roof of the pilot bore A by the hydraulic jacks 112, 112. By operating the various hydraulic devices, the head 4 may be rotated, the boom swung with respect to the head and the saw blade support swung with respect to the boom, and by trapping the oil in the hydraulic adjusting motors, the parts 35 may be positively locked in position. These and other manners of use and advantages of the improved tunnel saw will be clearly apparent to those skilled in the art. It will be noted further that in the forms of apparatus in which the outer 40 end of the boom is rotatable the plane of the cutter bar or saw blade can be brought into a position at right angles to the primary axis of boom swing, and accordingly that horizontal, shearing and inclined kerfs in advance of the machine may be cut in accordance with well known methods. These need not be described in detail since they will be clearly apparent to those skilled in the kerf-cutting art.

While I have in this application specifically described two forms which my invention may assume in practice, it will be understood that these forms of the same are shown for purposes of illustration, and that the invention may be further modified and embodied in various other forms without departing from its spirit or the scope of the appended claims.

What I claim as new and desire to secure by Letters Patent is.

1. In a kerf-cutting apparatus, a portable body, a head mounted on said body to rotate about a horizontal axis extending longitudinally of the body, an extensible structure pivotally mounted on said head to swing relative thereto, said boom structure swingable about its pivotal axis relative to said head into a position at right angles to the head axis, a cutter, a support for said cutter pivotally mounted on the outer extremity of said boom structure to swing relative thereto about an axis parallel with the pivotal axis of said boom structure, devices for extending and retracting said boom structure to move said cutter from and toward the head axis, and devices for swinging said boom structure and said cutter support about their respective pivotal axes.
2. In a kerf-cutting apparatus, a portable

body, a head mounted on said body to rotate about a horizontal axis extending longitudinally of the body, an extensible boom structure pivotally mounted on said head to swing relative thereto, said boom structure swingable about its 5 pivotal axis relative to said head into a position at right angles to the head axis, a cutter, a support for said cutter pivotally mounted on the outer extremity of said boom structure to swing relative thereto about an axis parallel with the 10 pivotal axis of said boom structure, hydraulic devices for extending and retracting said boom structure to move said cutter from and toward the head axis, and hydraulic devices for swinging said boom structure and 15 containing a reciprocable piston pivotally connected to said cutter support.

3. In a tunneling apparatus, a portable base, a cutter, and extensible supporting means for said cutter mounted on said base to turn about a horizontal axis extending longitudinally of said base for adjusting and moving said cutter to cut 25 with a circular cutting motion concentric tunnel bores of different diameters, said extensible supporting means comprising a rotatable head and a cutter supporting boom swingably mounted on said head and shortenable and extensible as to 30 length for supporting said cutter for movement into different cutting positions toward and from the head axis.

4. In a kerf-cutting apparatus, a portable base, a head rotatably mounted on said base for 35 rotation relative thereto about a horizontal axis, a boom pivotally mounted on said head to swing relative thereto, a second head mounted on said boom for rotation about the longitudinal axis of said boom, and a cutter carried by said second 40 head.

5. In a kerf-cutting apparatus, a portable base, a head rotatably mounted on said base for rotation relative thereto about a horizontal axis, a boom pivotally mounted on said head to swing 45 relative thereto, a second head mounted on said boom for rotation about the longitudinal axis of said boom, a cutter support pivotally mounted on said second head to swing relative thereto, and a cutter pivotally mounted on said swingable cutter support to swing relative thereto.

6. In a kerf-cutting apparatus, a portable base, a head rotatably mounted on said base for rotation relative thereto about a horizontal axis, a boom pivotally mounted on said head to swing 55 relative thereto, a second head mounted on said boom for rotation about the longitudinal axis of said boom, a cutter support pivotally mounted on said second head to swing relative thereto, and a cutter pivotally mounted on said swingable cutter support to swing relative thereto, said swingable cutter support being swingable about an axis at right angles to the axis of rotation of said second head, and said cutter being swingable about an axis at right angles to the pivotal axis 65 of said swingable cutter support.

7. In a tunneling apparatus, a portable base, rotary cutting means for cutting with a circular cutting motion tunnel bores of different diameters and comprising a cutter disposed in parallelism with the path of movement of said base with its forward end located rearwardly of the forward end of said base, said cutter comprising a cutter bar having mounted on its margin an endless cutter chain, and an adjustable sup- 75

- porting means for said cutter rotatable about a horizontal axis extending longitudinally of said base for adjusting the cutter into different cutting positions toward and from said longitudinal axis and for moving the cutter in a circular path about said longitudinal axis including an arm pivotally mounted to swing about an axis lying in a vertical plane extending transversely of said base and shortenable and extensible as to length for moving said cutter toward and from said longitudinal axis, and means for rotating said arm about said longitudinal axis and for extending said arm.
8. In a kerf-cutting apparatus, a portable base, a support mounted on said base for rotation relative thereto about a horizontal axis extending longitudinally of said base, an extensible arm pivotally mounted on said support to swing relative thereto about an axis at right angles to said support axis, said arm comprising telescopically arranged inner and outer arm portions, means for extending the outer arm portion relative to said inner arm portion to vary the length of said arm, and a cutter carried at the outer extremity of said arm.
9. In a kerf-cutting apparatus, a portable base, a support mounted on said base for rotation relative thereto about a horizontal axis extending longitudinally of said base, an extensible arm pivotally mounted on said rotatable support to swing relative thereto about an axis at right angles to the support axis, said arm comprising telescopically arranged inner and outer arm portions, means for extending the outer arm portion axially relative to said inner arm portion to vary the length of said arm, a cutter support pivotally mounted on the outer extremity of said arm to swing relative thereto about an axis parallel with the arm pivot axis, a cutter carried by said cutter support, means for swinging said arm relative to said rotatable support, and means for swinging said cutter support relative to said arm.
10. In a kerf-cutting apparatus, a portable base, a support mounted on said base for rotation relative thereto about a horizontal axis extending longitudinally of said base, an arm pivotally mounted on said support to swing relative thereto about an axis at right angles to the support axis, a head mounted on the outer extremity of said arm for rotation about the longitudinal axis of said arm, and a cutter carried by said rotatable head.
11. In a kerf-cutting apparatus, a portable base, a support mounted on said base for rotation relative thereto about a horizontal axis extending longitudinally of said base, an arm pivotally mounted on said rotatable support to swing relative thereto about an axis at right angles to the support axis, a head mounted on the outer extremity of said arm for rotation about the longitudinal axis of said arm, a cutter support pivotally mounted on said rotatable head on an axis at right angles to the axis of head rotation, and a cutter carried by said cutter support.
12. In a kerf-cutting apparatus, a portable base, a horizontal turntable on said base, a support mounted on said turntable for rotation about a horizontal axis at right angles to the axis of turntable rotation, an arm pivotally mounted on said rotatable support to swing about an axis at right angles to said support axis, a cutter head mounted on the outer extremity of said arm for rotation about the longitudinal axis of said arm, and a cutter carried by said rotatable head.
13. In a kerf-cutting apparatus, a portable base, a horizontal turntable on said base, a support mounted on said turntable for rotation about a horizontal axis at right angles to the axis of turntable rotation, an arm pivotally mounted on said rotatable support to swing relative thereto about an axis at right angles to the support axis, a cutter head mounted on the outer extremity of said arm for rotation about the longitudinal axis of said arm, a cutter support pivotally mounted on said rotatable head on an axis at right angles to the axis of head rotation, and a cutter carried by said cutter support.
- base, a horizontal turntable on said base, a support mounted on said turntable for rotation about a horizontal axis at right angles to the axis of turntable rotation, an arm pivotally mounted on said rotatable support to swing relative thereto about an axis at right angles to the support axis, a cutter head mounted on the outer extremity of said arm for rotation about the longitudinal axis of said arm, a cutter support pivotally mounted on said rotatable head on an axis at right angles to the axis of head rotation, and a cutter carried by said cutter support.
14. In a kerf-cutting apparatus, a portable base, a support mounted on said base for rotation about a horizontal axis extending longitudinally of said base, an arm pivotally mounted on said support to swing relative thereto about an axis at right angles to the support axis, a cutter head mounted on the outer extremity of said arm for rotation about the longitudinal axis of said arm, and a cutter pivotally mounted on said cutter head to swing relative thereto about an axis at right angles to the axis of head rotation.
15. In a kerf-cutting apparatus, a portable base, a support mounted on said base for rotation about a horizontal axis extending longitudinally of said base, an arm pivotally mounted on said support to swing relative thereto about an axis at right angles to the support axis, a cutter head mounted on the outer extremity of said arm for rotation about the longitudinal axis of said arm, a cutter support pivotally mounted on said rotatable head on an axis at right angles to the axis of head rotation, and a cutter pivotally mounted on said cutter support to swing relative thereto about an axis at right angles to the axis of head rotation.
16. In a kerf-cutting apparatus, a portable base, a horizontal turntable on said base, a support mounted on said turntable for rotation about a horizontal axis at right angles to the axis of turntable rotation, an arm pivotally mounted on said rotatable support for swinging movement on an axis at right angles to the support axis, a cutter head mounted on the outer extremity of said arm for rotation about the longitudinal axis of said arm, and a cutter pivotally mounted on said cutter head to swing relative thereto about an axis at right angles to the axis of head rotation.
17. In a kerf-cutting apparatus, a portable base, a horizontal turntable on said base, a support mounted on said turntable for rotation about a horizontal axis at right angles to the axis of turntable rotation, an arm pivotally mounted on said rotatable support for swinging movement on an axis at right angles to the support axis, a cutter head mounted on the outer extremity of said arm for rotation about the longitudinal axis of said arm, a cutter support pivotally mounted on said head on an axis at right angles to the axis of head rotation, and a cutter pivotally mounted on said cutter support to swing relative thereto about an axis at right angles to the axis of head rotation.
18. In a kerf-cutting apparatus, a portable base, a support mounted on said base for rotation about a horizontal axis extending longitudinally of said base, an extensible arm pivotally mounted on said rotatable support on an axis at right angles to the support axis, said arm comprising telescopically arranged inner and outer arm portions, a pair of hydraulic cylinders mounted on the opposite sides of said inner arm

portion and containing reciprocable pistons connected to said outer arm portion for extending said outer arm portion relative to said inner arm portion, and a cutter carried by said arm.

- 5 19. In a kerf-cutting apparatus, a portable base, a support mounted on said base for rotation about a horizontal axis extending longitudinally of said base, an extensible arm pivotally mounted on said rotatable support on an axis 10 at right angles to the support axis, said arm comprising telescopically arranged inner and outer arm portions, a pair of hydraulic cylinders mounted on the opposite sides of said inner arm portion and containing reciprocable pistons connected to said outer arm portion for extending said outer arm portion relative to said inner arm portion, a cutter carried by said arm, and means for swinging said arm about its pivot relative to said support comprising at least one hydraulic 15 cylinder pivotally mounted on said support on an axis parallel to the arm pivot axis and containing a reciprocable piston pivotally connected to the inner arm portion.

20. In a kerf-cutting apparatus, a portable base, a horizontal turntable on said base, a support mounted on said turntable for rotation about a horizontal axis at right angles to the axis of turntable rotation, a cutter supported by said rotatable support, a pair of hydraulic cylinders 25 mounted on said base each containing a reciprocable piston having a rearwardly extending piston rod, and connections actuated by said pistons and connected to said rotatable support and turntable for selectively rotating said support and turntable about their respective axes of rotation.

21. In a tunneling apparatus, a portable base, a head mounted on said base for rotation relative thereto about a horizontal axis extending longitudinally of said base, an arm extensible in 30 length pivotally mounted on said head to swing relative thereto about an axis at right angles to the head axis, said arm swingable about its pivotal axis relative to said head into a position wherein the longitudinal axis of the arm is at 35 right angles to the head axis, a cutter support pivotally mounted on the outer extremity of said arm to swing relative thereto about an axis parallel with the arm pivot axis, a kerf cutter carried by said cutter support, said arm and cutter support swingable about their respective pivotal axes to move said cutter into parallel cutting positions at different distances with respect to the 40 axis of head rotation, means for extending and retracting said arm when the latter is in said right angle position with respect to said head to move said kerf cutter from and toward the head axis, and means for rotating said head to move said cutter in a circular path in any of aforesaid 45 adjusted positions of the cutter with respect to the head axis to cut annular kerfs of different diameters.

22. In a tunneling apparatus, a portable base, a head mounted on said base for rotation about a horizontal axis extending longitudinally of said base, a boom structure extensible in length pivotally mounted on said head to swing relative thereto, said boom structure swingable about its pivotal axis relative to said head into a position wherein the longitudinal axis of said boom structure extends at right angles to the head axis, a kerf cutter, a support for said kerf cutter pivotally mounted on said boom structure to swing relative thereto about an axis parallel with the boom structure pivot axis, said cutter support 55 being swingable about its pivot relative to said

boom structure to move said kerf cutter into cutting planes parallel with and at varying distances from the head axis when said boom structure is moved about its pivotal axis relative to said head, devices for swinging said boom structure and said cutter support about their respective pivotal axes, devices for extending and retracting said boom structure when the latter is in said right angle position with respect to said head to move said kerf cutter from and toward the 10 head axis, and devices for rotating said head about its axis at a cutting speed to move said kerf cutter in a circular path to cut an annular kerf concentric with the head axis in any adjusted position of said kerf cutter relative to the 15 head axis.

23. In a tunneling apparatus, a portable base, a cutter, adjustable supporting means for said cutter mounted on said base to turn about a horizontal axis extending longitudinally of said base 20 for adjusting and moving said cutter, while the latter extends longitudinally forwardly in parallelism with said horizontal axis with its forward end disposed a substantial distance in advance of the rear end of said base, to cut with a circular cutting motion concentric tunnel bores of difference diameters, said adjusting means comprising an adjustable head, a cutter supporting boom extensible in length swingably mounted on said head, said boom being swingable with respect to said head from a position extending in the same direction with the head axis to a position at right angles to the head axis, a cutter support mounted on the outer extremity of said boom to swing relative thereto about an axis 35 parallel with the boom pivot axis, said support being swingable with respect to said boom from a position wherein the cutter extends lengthwise of said boom to a position wherein the cutter extends at right angles to said boom, and means 40 for extending and retracting said boom when the latter is in said right angle position with respect to said head for moving the cutter from and toward the head axis.

24. In an apparatus of the character described, 45 the combination comprising a frame, a cutter, an adjustable supporting structure mounted on said frame for supporting said cutter for adjustment about rectangularly related pivotal axes, and means for adjusting said supporting structure to 50 effect adjustment of said cutter selectively about said axes comprising fluid-actuated cylinder and piston devices mounted on said frame, and flexible connections operated by said cylinder and piston devices and operatively connected to said cutter-supporting structure, said cylinder and piston devices being common to the adjustment of said cutter about both of said axes.

25. In an apparatus of the character described, 55 the combination comprising a frame, a cutter, an adjustable supporting structure mounted on said frame for supporting said cutter for adjustment about rectangularly related pivotal axes one of which is on the horizontal, and means for adjusting said supporting structure to effect adjustment of said cutter selectively about said axes comprising fluid-actuated cylinder and piston devices mounted on said frame, and flexible connections operated by said cylinder and piston devices and operatively connected to said cutter-supporting 70 structure, said cylinder and piston devices being common to the adjustment of said cutter about both of said axes.

26. In an apparatus of the character described, 75 the combination comprising a frame, a cutter,

an adjustable supporting structure mounted on said frame for supporting said cutter for adjustment about rectangularly related pivotal axes, means for adjusting said supporting structure to effect adjustment of said cutter selectively about said axes comprising fluid-actuated cylinder and piston devices mounted on said frame, flexible connections operated by said cylinder and piston devices and operatively connected to said cutter-
10 supporting structure, said cylinder and piston devices being common to the adjustment of said cutter about both of said axes, and means for locking said cutter against adjustment about either one of said axes during adjustment of said cutter about the other axis.

27. In an apparatus of the character described, the combination comprising a frame, a cutter, an adjustable supporting structure mounted on said frame for pivotally supporting said cutter for adjustment about rectangularly related pivotal axes, and means for adjusting said supporting structure to effect adjustment of said cutter selectively about said axes comprising fluid actuated cylinder and piston devices mounted on said frame, annular grooved cable guiding members arranged coaxially with said pivots respectively, and flexible connections operated by cylinder and piston devices and operatively connected to said cutter-supporting structure, said flexible connections engaging the grooves in said annular guiding members, said cylinder and piston devices being common to the adjustment of said cutter about both of said axes.

28. In an apparatus of the character described, the combination comprising a frame, a cutter, an adjustable supporting structure mounted on said frame for pivotally supporting said cutter for adjustment about rectangularly related pivotal axes, said supporting structure comprising a support 35 rotatable on a horizontal axis and a cooperating support rotatable on an axis at right angles to said horizontal axis, means for adjusting said supports of said supporting structure to effect adjustment of said cutter selectively about said axes comprising a pair of parallel hydraulic cylinders 40 mounted on said frame and containing reciprocable pistons having rearwardly extending piston rods, guide sheaves carried by the rear ends of said piston rods, guide sheaves on said frame 45 and on one of said supports of said supporting structure, cable guiding members coaxial with said pivots and having cable guiding grooves and a pair of cables each secured at one end to said frame and at their other ends operatively 50 connected to said one of said supports and guided by said guide sheaves and said cable guiding members, and means for locking either one of said supports against pivotal movement about its pivot during pivotal movement of said other 55 support about its pivot.

29. In a tunneling apparatus, a portable base, an elongated kerf cutter, and means for supporting said kerf cutter and for moving the same orbitally to form an annular kerf of substantially uniform diameter from end to end and surrounding at least the receding end of said portable base, said means including a rotatable head mounted on said base at the receding end of the latter for turning on an axis extending longitudinally of said base, said elongated kerf cutter extending forwardly with respect to said base with its forward end in advance of the receding end of said base, supporting means for said kerf cutter intervening said rotatable head and said kerf cutter and operatively connected to said kerf cutter at the rearward end of the latter and including means for maintaining the kerf cutter during the formation of said annular kerf substantially parallel to said axis but spaced from it a distance exceeding the perpendicular distance to a line including said axis from the point in said portable base most remote from such line, and means for rotating said head on said axis at a rate to move said kerf cutter about said axis at a cutting speed.

30. In a tunneling apparatus, a portable base, an elongated kerf cutter, and means for supporting said kerf cutter and for moving the same orbitally to form an annular kerf of substantially uniform diameter from end to end and surrounding at least the receding end of said portable base, said means including a rotatable head mounted on said base at the receding end of the latter for turning on an axis extending longitudinally of said base, said elongated kerf cutter extending forwardly with respect to said base with its forward end in advance of the receding end of said base, supporting means for said kerf cutter intervening said rotatable head and said kerf cutter and operatively connected to said kerf cutter at the rearward end of the latter and including a cutter supporting boom pivotally connected to said rotatable head and an adjustable pivotal support for said kerf cutter on said boom for maintaining the kerf cutter during the formation of said annular kerf substantially parallel to said axis but spaced from it a distance exceeding the perpendicular distance to a line including said axis from the point in said portable base most remote from such line, and means for rotating said head on said axis at a rate to move said kerf cutter about said axis at a cutting speed.

31. In a tunneling apparatus, a portable base, an elongated kerf cutter, and means for supporting said kerf cutter and for moving the same orbitally to form an annular kerf of substantially uniform diameter from end to end and surrounding at least the receding end of said portable base, said means including a rotatable head mounted on said base at the receding end of the latter for turning on an axis extending longitudinally of said base, said elongated kerf cutter extending forwardly with respect to said base with its forward end in advance of the receding end of said base, supporting and adjusting means for said kerf cutter intervening said rotatable head and said kerf cutter and operatively connected to said kerf cutter at the rearward end of the latter and including means for maintaining the kerf cutter during the formation of said annular kerf substantially parallel to said axis but spaced from it a distance exceeding the perpendicular distance to a line including said axis from the point in said portable base most remote from such line, and means for rotating said head on said axis at a rate to move said kerf cutter about said axis at a cutting speed.

32. In a tunneling apparatus, a portable base, an elongated kerf cutter, and means for supporting said kerf cutter and for moving the same orbitally to form an annular kerf of substantially uniform diameter from end to end and

- surrounding at least the receding end of said portable base, said means including a rotatable head mounted on said base at the receding end of the latter for turning on an axis extending longitudinally of said base, said elongated kerf cutter extending forwardly with respect to said base with its forward end in advance of the receding end of said base, supporting and adjusting means for said kerf cutter intervening said 5 rotatable head and said kerf cutter and operatively connected to said kerf cutter at the rearward end of the latter and including means for maintaining the kerf cutter during the formation of said annular kerf substantially parallel to 10 said axis but spaced from it a distance exceeding the perpendicular distance to a line including said axis from the point in said portable base most remote from such line, said kerf cutter supporting and adjusting means including a boom 15 having means between its ends for altering its length and means for adjustably pivotally connecting said boom with said head and said cutter with said boom on parallel axes each providing for the disposition of the pivotally connected 20 members at right angles to each other or in substantial alinement with each other, and means for rotating said head on said head axis at a rate to move said kerf cutter about said axis at a cutting speed. 25
- 30 33. The method of forming a portion of a tunnel by removing material surrounding a pilot bore, which includes supporting within the pilot bore a support for a cutting instrumentality, operating said instrumentality to form an annular kerf surrounding the bore and spaced outwardly from the wall of the latter and at least in part underlying the material underlying said 35
- support, moving said support to a position in said bore not yet surrounded by an annular kerf, and removing material surrounded by said annular kerf. 5
34. The method of forming a portion of a tunnel by removing material surrounding a pilot bore, which includes supporting within the pilot bore a support for a cutting instrumentality, operating said instrumentality to sump the same longitudinally into the material surrounding said 10 bore and then moving the same bodily orbitally about an axis parallel to the axis of the bore to form an annular kerf surrounding the bore and spaced outwardly from the wall of the latter and at least in part underlying the material underlying 15 said support, moving said support to a position in said bore not yet surrounded by an annular kerf, and removing material surrounded by said annular kerf. 20
35. In a mining apparatus, a support, a revolute cutter support mounted on said first support for rotation about an axis extending longitudinally of said first support, a kerf cutter supported by said cutter support, and means for revolving said cutter support relative to said first support to move said kerf cutter into relatively inclined cutting planes including parallel cylinders mounted on said first support, pistons reciprocable in said cylinders and each having a piston rod carrying a pulley, a cable drum on said revolute support and cables each having an end fixed to said first support and their other ends fixed to said revolute support, said cables engaging said pulleys respectively and wound about said drums. 25 30 35

JOSEPH FRANCIS JOY.

CERTIFICATE OF CORRECTION.

Patent No. 2,229,086.

January 21, 1941.

JOSEPH FRANCIS JOY.

It is hereby certified that error appears in the printed specification of the above numbered patent requiring correction as follows: Page 1, first column, line 26, for the word "device" read --devices--; page 2, second column, line 24, for "swinging" read --swingable--; page 5, second column, line 67, for "mechanism" read --mechanisms--; page 7, first column, line 62, claim 1, after "extensible" insert the word --boom--; page 8, first column, line 73, claim 12, for "abou" read --about--; same page, second column, line 10, claim 13, for "mounited" read --mounted--; page 9, second column, line 65-66, claim 25, for "adjusting" read --adjustment--; page 10, first column, line 11, claim 26, for "adustment" read --adjustment--; same page, second column, line 10, claim 29, for "cutting" read --cutting--; lines 25, 26, and 37, claim 30, for "cutter" read --cutter--; page 11, first column, line 10, claim 32, for "cutter" read --cutter--; line 24, same claim, for "piovtally" read --pivotally--; and that the said Letters Patent should be read with this correction therein that the same may conform to the record of the case in the Patent Office.

Signed and sealed this 13th day of May, A. D. 1941.

(Seal)

Henry Van Arsdale,
Acting Commissioner of Patents.
